UNITED STATES PATENT OFFICE.

NICOLA DE RITIS, OF BINGHAMTON, NEW YORK.

BOTTLE-NECK-SHAPING MACHINE.

Application filed December 12, 1922. Serial No. 606,478.

To all whom it may concern:

Be it known that I, NICOLA DE RITIS, a subject of the King of Italy, residing at Binghamton, in the county of Broome and 5 State of New York, have invented certain new and useful Improvements in Bottle-Neck-Shaping Machines, of which the following is a specification.

This invention relates to certain new and 10 useful improvements in bottle neck shaping machines and has particular reference to a manually operable machine apparatus for providing an annular groove in the neck of a bottle while in a semi-plastic state.

15 Another object of the invention embodies in a bottle neck shaping or grooving machine of the type above set forth, the provision of electrically controlled devices for registering the number of bottles so grooved, 20 such a likable device being rendered operative upon the opening movement of gripping devices for receiving the neck of a bottle.

With the above general objects in view 25 and others that will appear as the nature of the invention is better understood, the same consists of the novel form, combination and arrangement of parts hereinafter more fully described, shown in the accompanying drawing and claimed.

In the drawing, wherein like reference characters designate corresponding parts throughout the several views,

Figure 1 is a top plan view of a bottle 35 neck shaping machine constructed in accordance with the present invention, the gripping jaws for the bottle neck being shown in section carried by a shaft supported gear wheel that meshes with a manually reciprocable rack bar to be rotated thereby, and further showing the electrical registering devices for indicating the number of bottles so grooved,

Figure 2 is a side elevational view of the 45 machine showing the side bars for the roller supported rack bar and the gripping jaws for the bottle neck,

Figure 3 is a cross sectional view taken on line III—III of Fig. 1 showing the roller 50 mounting for the rack bar,

Figure 4 is a face view of the gripping jaws,

Figure 5 is a fragmentary elevational view, partly in section showing the gear supporting the sectional gripping jaws and the 55 hinge mounting for said jaws,

Figure 6 is a cross sectional view taken on line VI—VI of Fig. 5 showing the tensioned springs for retaining the jaws in closed position, and

Figure 7 is a fragmentary detail sectional view showing the gripping jaws in open position against the spring tension thereon and engaging the contact members for the electrical registering mechanism.

Referring more in detail to the accompanying drawings, and particularly to Fig. 1 there is illustrated a bottle neck shaping or grooving machine embodying a base plate 1 having a lateral plate extension 2 for supporting the entire mechanism of the device. A tubular bearing 3 supported by straps 4 is disposed above the plate section 2, the tubular bearing rotatably supporting a shaft 5, a gear wheel 6 fixed to the projecting end thereof and overlying the plate section 1.

Gripping jaws for the neck of the bottle B supported by the clamp C are carried by the shaft 5 at a point spaced outwardly of 80 the plate section 1, said jaws being formed of semi-circular sections forming a cup-shaped or socketed member that are hinged as at 8 to the bracket head 9 fixed to the shaft 5 as shown in Fig. 5. The jaw sections 7 normally occupy a closed position as indicated in Figs. 1 and 6 by coil springs 10 positioned between the rear ends of said jaw sections and the bracket head 9. Each jaw section 7 carries a handle 11 to facilitate opening movement thereof against the tension of the spring 10. Each jaw section 7 is further provided with a spring arm 12 secured to the inner bottom wall thereof as at 13 and carries upon the inner side adjacent the outer end, a knob or block 14 of metal or stone for forming an external annular groove in the neck of the bottle B upon rotation of the clamping jaw 7. To center or properly position the neck of the 95 bottle in the clamping jaws, an axial pin 15 projects from the end of the shaft 5 and extends into the bottle neck as shown in Fig. 1.

The mechanism for rotating the shaft 5

and the clamping jaws 7 associated therewith embodies a rack bar cooperating with the gear wheel 6, there being provided a supporting frame 16 mounted upon the base plate section 1 and carrying spaced horizontal guide arms 17 flared in opposite outwardly directions at one end thereof as at 18, the rack bar 19 carrying roller bearings 20 adjacent each end thereof riding between 5 the guide bars 17 as shown in Figs. 1 to 3 inclusive, while a gripping handle 21 is carried by the outer end of the rack bar to effect reciprocation thereof. In order to prevent the complete withdrawal of the rack 10 bar 19 from the guide bar 17, the inner terminal tooth 19^a of said rack bar is formed of a greater height than the remaining rack teeth for engagement with the gear wheel 6 to prevent further movement of said rack 15 bar.

In the operation of the device, the handle 21 is gripped for reciprocating the rack bar 19 and said rack bar being in mesh with the gear wheel 6 that is fixed to the shaft 5, said 20 shaft is rotated and carries therewith the gripping jaws 7 for the neck of the bottle B. The bottle carried by the clamp support C is moved into the clamping jaws 7 and centered thereby, by the pin 15, the 25 spring arms 12 carrying the shaping knobs 14 engaging the outer face of the bottle neck for forming an annular groove therein upon rotation of the clamping jaws. In removing and placing the neck of a bottle in the 30 clamping jaws 7, said jaws are moved upon their hinge connections 8 with the bracket head 9 of the shaft 5 and when said jaws are open, one of the same cooperates with electrical devices for registering the number of 35 bottles being grooved.

The registering mechanism includes an indicator casing 22 having wired connections with the battery 23 and the spaced contacts 24. The contacts 24 are disposed adjacent one of the hinged clamping jaws 7 and in the path of movement thereof, so that when said jaws are opened, the contact points will be brought into engagement for closing the circuit and numerically increasing the indications upon the register 22.

While there is herein shown and described the preferred embodiment of the present invention it is nevertheless to be understood that minor changes may be made

therein without departing from the spirit 55 and scope of the invention as claimed.

What I claim is:—

1. In a bottle neck shaping machine, a supporting base plate, a shaft journaled therein, a gear on said shaft, a supporting frame on said base plate including spaced horizontally extending pairs of guide arms positioned at right angles to the axis of said shaft, a rack bar operatively engaging said gear roller bearings carried by said rack bar and projecting between said pairs of guide arms for permitting reciprocation of the rack bar, a handle on said rack bar for manually operating the same to cause rotation of said shaft, bottle neck clamping jaws carried by said shaft, said clamping jaws being formed of hinged sections carried by said shaft and rotatable therewith, spring devices for normally holding the clamping jaws in a closed position, a spring arm carried by each clamping jaw section, and a shaping knob carried by the inner face of the outer end of each spring arm for engagement with the external surface of a bottle neck for forming an annular groove therein 70 upon rotation of said shaft.

2. In a bottle neck shaping machine, a supporting base plate, a shaft journaled therein, a gear on said shaft, a supporting frame on said base including spaced horizontal guide arms extending at right angles to the axis of said shaft, a rack bar operatively engaging said gear reciprocally carried by said supporting frame, a handle on said rack bar for manually operating the same to cause rotation of said shaft, semi-circular bottle neck clamping jaws carried by said shaft, said semi-circular jaws being hingedly connected to said shaft and rotatable therewith, said jaws normally forming a cup-shaped member adapted to receive the neck of a bottle, spring devices for normally holding said jaws in their cup-shaped formation, a spring arm carried by each clamping jaw section, and a shaping knob carried by the inner face of the outer end of each spring arm for engagement with the external surface of a bottle neck for forming an annular groove therein upon rotation of said shaft.

In testimony whereof I affix my signature.

NICOLA DE RITIS.
